THREE JAW VISE

Filed Dec. 18, 1947

UNITED STATES PATENT OFFICE

2,552,094

THREE JAW VISE

Wesley M. Hamon and Maurice O. Pearson,
East Los Angeles, Calif.

Application December 18, 1947, Serial No. 792,384

1 Claim. (Cl. 81—33)

1

Our invention relates to three-way vises and has for its principal object, to provide a simple, inexpensive and highly effective bench vise having three readily adjustable jaws, two of which are mounted so as to swing on vertical axes, thus enabling the vise jaws to be readily positioned so as to engage and clamp, at three points, work pieces, or objects of varying shapes and sizes, as well as straight pieces of work such as bars, tubes, rods and the like.

Further objects of our invention are, to provide a vise of the character referred to, which is swivelled or mounted so as to swing on a fixed base and thereby facilitate the handling and anchoring of work differing in length and shape, and further to provide simple means for readily adjusting the three jaws of the vise toward and away from each other.

With the foregoing and other objects in view, our invention consists in certain novel features of construction and arrangement of parts which will be hereinafter more fully described and claimed and illustrated in the accompanying drawing, in which:

Fig. 1 is a top plan view of our improved vise with the jaws closed.

Fig. 2 is a side elevation.

Fig. 3 is a cross section taken on the line 3—3 of Fig. 2.

Fig. 4 is a detail section taken on the line 4—4 of Fig. 3.

Referring by numerals to the accompanying drawing, which illustrates a preferred embodiment of our invention, 10 designates a base block adapted to be fixed on a bench or suitable support. Mounted to swing or swivel on a pin or stud 11 projecting upwardly from said base, is a block 12 which functions as the vise body and jaw carrier.

Formed integral with or fixed to block 12, are diametrically opposite brackets 13, carrying outwardly projecting arms or bars 14 which serve as rails for supporting the posts 16, which carry the oppositely disposed jaw blocks 18.

Mounted to rotate freely on studs which project upwardly from the tops of post members 16, are blocks 18, the inner or work contacting faces of which carry fixed liners or face plates 19, of hardened metal.

The ends of blocks 18 disposed adjacent the third jaw, hereinafter described, carry fixed liners 20 of hardened metal.

The lower portions of posts 16 are provided with horizontally disposed slots 21, T-shape in cross section, the upper portions of which receive 55 the bars 14.

2

Formed through the upper portion of block 12, is a horizontal bore 22, through which passes a rod 23, which is held against longitudinal movement by pins 24, driven into the top of block 12 and which pass through a circumferential groove 25 formed at the center of said rod (see Fig. 4). Rod 23, to one side of groove 25, has a right hand thread 26 and on the other side a left hand thread 27 and these threaded portions pass through correspondingly threaded bores 28 in posts 16.

One end of rod 23 carries a sliding cross handle 29a. Screw seated in a horizontal bore 29 formed through block 12 just below and at right angles to rod 23, is a threaded rod 30, one end thereof carrying a sliding cross handle 31, and loosely mounted on said rod is a post 32, the upper end of which curves toward blocks 18, to form a jaw 33 and seated in the face thereof is a hardened metal plate 34. A horizontally disposed bar 35, projects from the lower portion of post 32 and slides freely through an aperture 36 in vise body or block 12.

In using the vise for straight work, such as rods, rails, tubes and the like, handle 29a and screw rod 23 are manipulated to move posts 16 toward each other, so that face plates 19 are in contact with one another, or spaced slightly apart, and after the work has been placed against said face plates, handle 31 and screw rod 30 are manipulated to move post 32 and jaw 33 toward the work, thereby firmly clamping same between the face plates 34 and 20 of said jaws.

To grip and hold an object or piece of work of irregular shape, for instance, a casting, screw rods 23 and 30 are rotated so as to separate these jaws and the blocks 18 are now shifted on their axes, the studs 11, so as to move face plates 19 into angular positions relative to each other and to face plate 34 and after the work has been placed between the three plates, proper manipulation of screw rods 23 and 30 will move the jaws so that the face plates thereon will engage and firmly clamp the work at three different points.

An especially desirable feature of our invention is the employment of the pivoted blocks 18 on two of the jaws inasmuch as such structure enables said blocks to automatically adjust themselves when moved into clamping engagement with work of irregular shape.

Thus it will be seen that we have provided a three jaw vise that is simple in structure, inexpensive of manufacture and very effective in performing the functions for which it is intended.

Minor changes in the size, form and construction of the various parts of our improved three

jaw vise may be made and substituted for those herein shown and described, without departing from the scope of the invention, as set forth in the appended claim.

We claim as our invention:

In a three jaw vise, a base, horizontally aligned arms projecting from opposite sides of said base, posts guided for sliding movement on said arms, blocks mounted for rotation on said posts and having a plurality of jaw faces, hardened metal liners on adjacent faces of said blocks, a horizontal rod having right and left hand threaded portions respectively engaging corresponding bores in said posts, a handle loosely carried by one end of said rod, means seated in said base 15 and engaging said threaded rod to hold same against longitudinal movement, a bar slidable through said base below and at right angles to the horizontal guiding axis of the arms thereon, a third jaw integral with said sliding bar and 20

having a work-engaging face disposed at the same height as the jaw faces of said blocks, a screw rod swiveled in said third jaw and threaded into said base, and a handle on said screw rod.

WESLEY M. HAMON.
MAURICE O. PEARSON.
